VACUUM CLEANER

Lester C. Smith, West Hartford, Conn., assignor
to The Spencer Turbine Company, Hartford,
Conn., a corporation of Connecticut

Application November 18, 1936, Serial No. 111,463

6 Claims. (Cl. 15—16)

My invention relates to the class of apparatus that is more particularly adapted for cleaning floor spaces and similar surfaces, and an object of my invention, among others, is the production of an apparatus which may be used as a stationary fixture or which may be used as a portable device and to provide means for readily transforming the one to the other; and a further object of my invention is to provide an apparatus of this type that shall be particularly efficient in operation.

One form of an apparatus embodying my invention and in the construction and use of which the objects herein set out, as well as others, may be attained, is illustrated in the accompanying drawing in which

Figure 1 is a side view of my improved pneumatic cleaner.

Figure 2 is a top plan view.

Figure 3 is an end view.

Figure 4 is a view in end elevation looking at the opposite end from that shown in Figure 3.

In the accompanying drawing my improved vacuum cleaner is shown as mounted in a frame comprising uprights 6 in the form of posts located at its opposite four corners and united by cross pieces 7 and side bars 8 of any suitable material joined to the posts above their lower ends in any desired manner, said posts thereby constituting legs. A dust separator 9 comprising a part of the vacuum cleaning apparatus is mounted on the frame, preferably at the rear end thereof, and this separator, the case only of which is shown herein, may be of any suitable construction containing any common and well known means for separating the dust and dirt from the air which is collected in the operation of the device. Hand holes 10 closed by covers 11 are located in suitable positions for entrance to the case of the separator. Conveying tubes 12 for conducting dirt and dust collected by the apparatus lead into the separator or case 9 near the bottom thereof and an outlet conduit 13 extends from the top of the separator or case 9 into one end of a vacuum pump 14 supported by the frame preferably atop a motor 15 resting by choice on the bottom of the frame. The vacuum pump 14 may be of any desired construction, the case of such pump herein shown being formed to contain disks with vanes of the centrifugal type, the inner mechanism not being shown, but it being well understood that the air is admitted in the eye of the case and is thrown outward by the centrifugal force to the periphery thereof. The air drawn in by the vacuum pump after the dust and dirt have been separated there-

from in the separator 9 is exhausted through an exhaust pipe 16. The motor 15 may be of any desired construction and operation comprising a shaft 17 with a pulley 18 secured thereto and connected as by a belt 19 with a pulley 20 secured to a shaft 21 of the centrifugal fan within the case or vacuum pump 14. The apparatus thus far described comprises the vacuum cleaner in a stationary sense, it being understood that when so used a suitable cleaning tool or tools will be connected with the conveying tubes 12 for the supply of the collected material to the dust separator or case 9. In order to adapt the apparatus for portable purposes the frame is so constructed that the platform on which the separator and motor rest is located above the floor or other similar surface so that the body 22 of a truck 23 may be backed under said platform. The body 22 of the truck has well known means which are raised into contact with a load to be carried by the truck, the details of such apparatus not being shown herein, it being sufficient to state that the truck is provided with such raising means which are well understood by those skilled in the art. The truck is provided with wheels 24, a motor 25 for propelling it, a platform 26 on which the operator may stand and a steering wheel 27 by which the truck, and in fact the apparatus as a whole, may be guided.

A collecting nozzle 28 is supported by wheels 29 located at its opposite ends, and also by a lifting lever 30 pivotally attached at one end to a post 31 secured to and rising from the nozzle, said lever being fulcrumed on a bar 32, the opposite end of said lever having a foot pad 33 overlying the platform 26 and accessible to the foot of the operator of the truck. The bar 32 is supported at its opposite ends on rollers 34 and is connected by rods 35 with clamps 36, such clamps preferably being of the ordinary C-type tightly clamped to the edge 40 of the platform 26. The rods preferably at their rear ends pass loosely through the clamps and springs 37 located on the rods afford a yielding connection between the collecting frame or unit and the truck, collecting frame or unit comprising 45 the nozzle 28, the bar 32, the rods 35 and connected parts.

The conveying tubes 12 are attached at their front ends to the nozzle 28 intermediate its ends, and as shown in Figs. 2 and 4 of the drawing. 50

The operation of the device will be readily understood from the foregoing description taken in connection with the accompanying drawing, it being briefly stated that hose with cleaning nozzles will be attached to that part of the conveying

tubes 12 preferably located on the frame of the cleaner when used as a stationary cleaner. For portable purposes the front sections 38 of such tubes are removably connected to the rear sections 12 preferably at the front end of the frame, and when so equipped the sections 38 of the conveying tubes are connected to the sections 12 after the collecting frame has been positioned in front of the platform 26. The clamps 36 are secured to the edges of said platform and the apparatus is now ready for use. As it is moved along a floor or similar surface, should an obstruction be encountered, the nozzle 28 may be readily lifted by pressure of the operator's foot upon the pad 33 and release of such pressure will at once return the nozzle to its former cleaning position.

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim:

1. A vacuum cleaning apparatus comprising a separating unit consisting of a supporting frame including a platform at the bottom of the frame and means for supporting said frame in an elevated position with a clear unobstructed space underneath said frame, said unit also including a dust separator mounted on said platform and a vacuum pump operatively connected therewith, means on said frame for operating said pump, a dirt conveying tube supported on said frame and connected with said separator, a transporting unit comprising a truck having a platform received in said space and also having lifting means to lift said supporting frame, said transporting unit also including a collecting nozzle coupled to said truck as a permanent part of the collecting unit, a tube connected with said nozzle and carried by said truck as an integral part of the collecting unit and removably connected with said dirt conveying tube as a means for uniting the two units as a complete working apparatus.

2. A vacuum cleaning apparatus comprising a separating unit consisting of a supporting frame, a dust separator and a vacuum pump operatively connected and mounted on said frame, means on said frame for operating said pump, and a dirt conveying tube connected with said separator and adapted to receive a connection to a cleaning tool at the end opposite the separator, and a transporting unit comprising a transporting frame, a collecting nozzle coupled to said transporting frame, a tubular connection mounted on said transporting frame and extending from and communicating with said nozzle, means detachably attaching said connection to the end of said dirt conveying tube, and means to support said supporting frame in an elevated position with a clear and unobstructed space thereunder in which is received said transporting frame, the latter having elevating means to lift said supporting frame of said separating unit.

3. A vacuum cleaning apparatus comprising a separating unit including a supporting frame,

a dust separator and a vacuum pump operatively connected and mounted on said supporting frame, means on said frame for operating said pump, said frame including a platform raised above the bottom of the frame with a clear and unobstructed space underneath it, a dirt collecting tube attached to said frame and connected with said separator, a collecting unit including a portably mounted collecting frame for support of a collecting nozzle, a nozzle coupled to and supported by said collecting frame, a tubular connection extending from said nozzle, means detachably attaching said connection to said dirt collecting tube, and a transporting unit including a truck having a platform, means yieldingly securing said collecting unit to said platform, the latter being adapted for movement under said supporting frame and having elevating means to lift said supporting frame.

4. A vacuum cleaning apparatus comprising a supporting frame, a dust separator and a vacuum pump operatively connected and mounted on said supporting frame, means on said frame for operating said pump, a portably mounted collecting frame for support of a collecting nozzle, a nozzle coupled to and supported by said collecting frame, a tubular connection extending from said nozzle, means detachably attaching said connection to said supporting frame in communication with said separator, a platform comprised in said supporting frame, means for supporting said platform in an elevated position above the bottom of said supporting frame with a clear and unobstructed space under said bottom to receive the body of a truck thereunder, and a truck coupled to said collecting frame and having elevating means to lift said platform, and means connected with said nozzle and accessible from the platform of said truck for lifting said nozzle.

5. In combination with the supporting frame of a vacuum cleaning apparatus including a platform for an operator of said apparatus, a portably mounted collecting frame coupled to said supporting frame and including a bar having rollers for supporting said frame, a lifting lever pivotally mounted on said collecting frame, a nozzle pivotally supported by said lever, a tubular connection extending from said nozzle, and means detachably attaching said connection to said supporting frame, one end of said nozzle supporting lever being accessible from said platform, and means detachably attaching said bar to said platform.

6. In combination with the supporting frame of a vacuum cleaning apparatus, a portably mounted collecting frame coupled to said supporting frame and including a bar having rollers at opposite ends, a nozzle movably attached to said bar and having rollers at its opposite ends, a lifting lever pivotally mounted on said bar and attached at one end to said nozzle, and having a foot pad at its opposite end, a tubular connection extending from said nozzle, means detachably attaching said connection to said supporting frame, and means detachably connecting said bar to the platform of said portably mounted collecting frame.

LESTER C. SMITH
